ELECTRICAL CONNECTION MEANS

Harry A. Douglas, Bronson, Mich., assignor to
Kingston Products Corporation, a corporation of
Indiana

Application July 17, 1935, Serial No. 31,808

9 Claims. (Cl. 173—328)

My invention relates to electrical connection means, and more particularly to means for receiving conductor terminals of the snap type, and the principal object of my invention is to provide new and improved electrical connection means of these types. In the drawing accompanying this specification and forming a part of this application, I have shown for purposes of illustration, several forms which my invention may assume. In this drawing:

Figure 1 is a perspective view of one embodiment of my invention.

Figure 2 is a longitudinal sectional view of the embodiment shown in Figure 1, with a plug conductor terminal added.

Figure 3 is a perspective view of another embodiment of my invention.

Figure 4 is a longitudinal sectional view of the embodiment shown in Figure 3.

Figure 5 is a perspective view of another embodiment of my invention, and

Figure 6 is a longitudinal sectional view of the embodiment shown in Figure 5.

Referring in detail to Figures 1 and 2 of the drawing, there is here shown a terminal post 10 mounted on a base 11, fragmentarily shown. The terminal post 10 comprises a body portion 12 formed of a single piece of sheet metal stock bent into generally S-shape. The S-shaped body portion 12 comprises, as viewed in Figures 1 and 2, two spaced generally horizontal walls 13, 14 integrally joined at one end by a vertical wall 15, the lower horizontal wall, 14, being spaced from another horizontal wall or foot, 16, below the horizontal wall 14, and integrally connected thereto by a vertical wall 17. The uppermost horizontal wall, 13, is provided with a recess 18 here shown as in the form of a portion of a cylindrical surface formed by pressing the wall 13 upward locally. The surface of the recess 18 may be considered as forming a lateral extension of a margin of an aperture 19 formed in the uppermost vertical wall 15.

The lower spaced horizontal walls, 14, 16, are provided with aligned circular apertures 20, 21, the aperture 21 in the wall 16 being somewhat larger than the aperture 20 in the wall 14. The axis of the apertures 20, 21 approximately intersects the axis of the aperture 19 and recess 18. Seated upon the margin of the lower aperture 21 is a washer 22, here shown as having its central portion 23 dished downwardly toward a central aperture 24 in the washer. The downwardly dished portion 23 of the washer 22 serves to center the washer with respect to the margin of the aperture

21. The washer 22 serves as an abutment for one end of a helical spring 25, the other end of which bears against a flange 26 forming part of a biasing means 27 cooperable with a plug conductor 28 insertable in the recess 18 and aperture 19.

The biasing means 27 is here shown as provided with a dome-shaped head 29, fitting slidably through the aperture 20 in the horizontal wall 14, a cylindrical shank 30 disposed within the helical spring 25, and the collar or flange 26 intermediate the head 29 and the end of the shank 30. The dome 29 projects above the upper surface of the horizontal wall 14. The length of the shank 30 is here shown as such that the lower end of the shank is somewhat below the upper level of the rim of the washer 22. With the rim of the washer 22 disposed concentrically with the aperture 21 in the wall or foot 16 of the terminal post, the aperture 24 in the washer is in alignment with the shank 30 of the biasing means 27, but somewhat spaced therefrom.

The foot 16 may be provided with an aperture 31 through which a screw 32 or any other suitable fastening means may be disposed to fasten the terminal post 10 to the base 11. In order to prevent the foot 16 of the terminal post 10 from turning about the fastening means 32, the foot 16 may have a portion 33 struck downwardly therefrom and fitting in a recess 34 in the upper face of the base 11.

The terminal post 10, illustrated in Figures 1 and 2, cooperates with the plug conductor terminal 28 as follows. The plug conductor terminal 28 is here shown as having a generally cylindrical portion 35 and a frusto-conical end 36, the cylindrical portion 35 being provided with an annular furrow 37. The plug conductor terminal 28 may be fastened to a conductor 38 disposed therein, by swaging, as indicated by swedge indentations 39. When the plug conductor terminal 28 is aligned with the mouth of the recess 18 and moved toward the right as viewed in Figure 2, the frusto-conical end 36 causes the dome-shaped portion 29 of the biasing means 27 to be cammed downwardly against the bias of the spring 25. Further inserting movement will cause the dome-shaped portion 29 of the biasing means 27 to snap into the annular furrow 37 of the plug conductor terminal 28. When the dome 29 of the biasing means is in engagement with the furrow 37, the collar 26 is desirably not in engagement with the lower side of the horizontal wall 14, so that the spring 25 is free to cause the biasing means 27 to firmly press into engagement with a surface of the recess 18 parts of the plug con-

ductor terminal disposed in the recess. The plug conductor terminal 28 may of course be removed by simply pulling the plug conductor terminal out of the recess 18, causing the dome 29 of the biasing means 27 to be cammed downwardly and disengaged from the furrow 37.

In assembling the terminal post 10, shown in Figures 1 and 2, the biasing means 27 may be brought to the position shown in Figure 2 by a combined motion of translation and rotation, that is, the biasing means 27 may be held at an angle to the vertical, as viewed in Figure 2, with the dome-shaped portion 29 about to be inserted through the lower entrance of the aperture 20 in the horizontal wall 14, and the biasing means then swung into the position shown in Figure 2, it being assumed that the spring 25 has been previously assembled with the shank 30 of the biasing means. When the biasing means 27 and the spring 25 are in the position shown in Figure 2, the spring may be held compressed so that the washer 22 can then be slid underneath the end of the shank 30 and under the lower end of the spring 25 to the position in which the rim of the washer 22 is concentric with the margin of the aperture 21 in the foot 16. The spring 25 may then be released so that its lower end abuts the top of the washer 22. The parts are then held assembled with the body of the post 10 against unintentional disassembly.

Referring now to Figures 3 and 4, which show another embodiment of my invention, a terminal post, 40, here shown is adapted for the reception of at least two plug conductor terminals. (In Figures 3 and 4 parts analogous to the parts of Figures 1 and 2 are designated with the same reference numerals with the suffix *a*.) To this end a vertical wall 15a is made of greater width than the wall 15 of Figures 1 and 2 and provided with two apertures 19a. The vertical wall 15a is integral with a generally horizontal wall 13a, which is here shown as shaped to form channel portions, the inside surfaces 18a of which are arcuate in cross-section and may be considered as forming extensions of the upper portions of the apertures 19a. As in the case of the embodiment of Figures 1 and 2, the body portion 12a of the post 40 further comprises a channel-shaped portion having spaced horizontal walls 14a, 16a integrally joined by a vertical wall 17a, the wall 16a serving as a foot for the terminal post. In the instance illustrated, the horizontal wall 16a has an apertured extension 41 which may be fastened to a base 11a in a manner already described in connection with Figures 1 and 2.

The post 40 is provided with two biasing means 27a, each biasing means 27a having a dome-shaped portion 29a, a shank 30a, and a collar 26a, the dome-shaped portions 29a of the biasing means being adapted to extend through circular apertures 20a in the horizontal wall 14a of the terminal post, so positioned that the domes 29a of the biasing means 27a will be cooperable with plug conductor terminals disposed in the recesses 18a of the channels of the wall 13a.

In the embodiment of Figures 3 and 4 the foot 16a of the terminal post 40 is provided with circular apertures 42 into which the ends of the shanks 30a of the biasing means are adapted to slidably fit. The shanks 30a of the biasing means 27a are surrounded by helical springs 25a, the upper ends of which engage the collars 26a and the other ends of which engage the upper surface of the foot 16a. The proportion of the parts is such that when the springs 25a bias the collars of the biasing means

against the lower side of the horizontal wall 14a, the lower ends of the shanks are slightly below the margins of the apertures 42 in the foot 16a.

The manner in which the terminal post cooperates with plug conductor terminals will be understood from what has been stated in connection with Figures 1 and 2.

In assembling or disassembling the biasing means 27a from the body portion 12a of the terminal post 40, the horizontal walls 14a, 16a of the channel-shaped part of the body portion 12a may be slightly sprung apart, so that the lower end of the shank 30a of the biasing means 27a will clear the upper margin of the aperture 42 in the foot 16a of the terminal post, whereupon the biasing means 27a, along with the spring 25a may be disassembled from or assembled with the body portion 12a, by relative motions, with respect to the body portion of the terminal post, such as have already been described in connection with Figures 1 and 2.

Referring now to Figures 5 and 6, in which parts analogous to those in Figures 1, 2, 3, and 4 are designated with the same reference numerals with the suffix *b*, these figures show another embodiment of my invention, a terminal post 43 here shown having a body portion 12b comprising a channel-shaped part having spaced horizontal walls 14b, 16b, integrally joined by a vertical wall 17b. The horizontal wall 14b is provided with an aperture 20b adapted to receive the dome-shaped portion 29b of a biasing means 27b identical with the biasing means 27a of Figures 3 and 4, and the wall or foot 16b is provided with an aperture 42b adapted to slidably receive the end of the shank 30b of the biasing means. A spring 25b is also provided for the biasing means 27b. The body portion 12b is further provided with a vertical wall 15b, integral with the horizontal wall 14b and extending therefrom somewhat closer to the axis 40 of the biasing means 27b than the walls 15 and 15a with respect to the biasing means 27 and 27a. The vertical wall 15b has an aperture 19b, the axis of which is in alignment with and at right angles to the axis of the biasing means 27b. The vertical wall 15b is here shown as provided with a lateral extending flange 13b, arcuate in cross-section, the inner surface 18b of which forms an extension of the upper portion of the aperture 19b. The flange 13b may be formed by metal drawn out in forming the aperture 19b.

The operation of the embodiment of Figures 5 and 6 will be apparent from what has already been stated in connection with Figures 1 through 4.

Terminal posts of the form of Figures 1, 2, 5, and 6 may also be constructed to receive more than one plug conductor terminal, as will be apparent to those skilled in the art from a consideration of the embodiment shown in Figures 3 and 4.

While the plug conductor terminal has been described as insertable into the terminal posts 10, 40, and 43 from the left hand side thereof, as viewed in Figures 2, 4, and 6, it will be apparent that the plug conductor terminal may be inserted into these posts from the right hand side, through the apertures 19, 19a, and 19b. In the case of the embodiment shown in Figures 5 and 6, it is preferable to assemble the plug conductor terminal 70 with the terminal post 43 from the right hand side, as viewed in Figure 6.

From the foregoing it will be apparent to those skilled in the art that the illustrated embodiments of my invention provides new and improved elec- 75

trical connection means, readily and conveniently constructed and assembled, and accordingly, each accomplishes at least the principal object of my invention. On the other hand, it also will be obvious to those skilled in the art that the illustrated embodiments of my invention may be variously changed and modified, or features thereof, singly or collectively, embodied in other combinations than those illustrated, without departing from the spirit of my invention, or sacrificing all of the advantages thereof, and that accordingly, the disclosure herein is illustrative only, and my invention is not limited thereto. It is also to be understood that the term, conductor terminal, includes not only a plug conductor terminal or separate terminal secured to a conductor, but also the bare end of a conductor wire or deformation thereof.

I claim:

1. Receptacle means for receiving and holding a plug conductor terminal of the snap type, comprising: a body portion having a recess for receiving a plug conductor terminal; means for biasing a plug conductor terminal against a wall of said recess, comprising detent means and resilient means for urging said detent means to operative position; spaced members; said detent means, when moved to operative position, having one end guided by one of said spaced members, and the other end terminating short of the other of said members; and washer means provided with an aperture for guiding said other end of said detent means and being cooperable with said other of said members to hold said biasing means in assembled relation with said body.

2. Receptacle means, comprising: a pair of walls connected in spaced relation, at least one being apertured, and having an angular portion extending in a direction away from said walls, said portion being apertured for receiving a conductor terminal; and biasing means, comprising a detent member having a portion extending through the aperture in said one wall for cooperation with a conductor terminal disposed in the aperture in said angular portion, said detent member having also a shank integral with said detent portion and an abutment formed on said shank and engageable with said one wall, for limiting the extent of said detent portion through the aperture in said one wall, said biasing means further comprising a spring disposed on the shank of said detent member and interposed between the other of said spaced walls and said detent member abutment, for urging said detent member to operative position.

3. Receptacle means, comprising: a body, formed of a single strip of sheet-metal bent to generally S-shape, the part of said body connecting one of the extremity portions and the intermediate portion being apertured to receive a conductor terminal and said one extremity portion being curved to form a continuation of at least a part of the marginal outline of said aperture, so as to provide a bearing surface for the conductor terminal, and the intermediate portion of said body having also an aperture disposed transversely with respect to the aperture in said connecting part; and biasing means, comprising a detent member working through the aperture in said intermediate portion, and a spring bearing against the other extremity portion of said body, and constructed and arranged to urge said detent member to bear against a conductor terminal in the aperture in said connecting portion, and to

press the conductor terminal against said bearing surface.

4. Receptacle means, comprising: a pair of spaced-apart walls, connected so as to be resiliently movable with respect to each other, at least one being apertured and having an angular portion extending in a direction away from said walls, said portion being apertured for receiving a conductor terminal; detent means interposed between said spaced-apart walls, having one end working through the aperture in said one wall for cooperation with a conductor terminal disposed in the aperture in said angular portion, and an abutment engageable with said one wall to limit the extent of said one end of said detent means through the aperture in said one wall, said detent means being of a length greater than the space between said walls, so that said walls must be sprung apart to provide for assembly or disassembly of said detent means; and spring means, constructed and arranged to urge said detent means abutment to engagement with said one wall.

5. Receptacle means, comprising: a pair of spaced-apart walls, connected so as to be resiliently movable with respect to each other, and each being apertured, at least one wall having an angular portion extending in a direction away from said walls, said portion being apertured for receiving a conductor terminal; detent means, interposed between said spaced-apart walls, and having its ends working through the apertures in respective walls, one end being in position to cooperate with a conductor terminal disposed in the aperture in said angular portion, said detent means having also an abutment adjacent said one end engageable with said one wall to limit the extent of the adjacent end of said detent means through the aperture in said one wall, said detent means being of such a length that said walls must be sprung apart to provide for assembly or disassembly of said detent member; and spring means, constructed and arranged to urge said detent means abutment to engagement with said one wall.

6. Receptacle means, comprising: a body, having a portion provided with an aperture for receiving a conductor terminal, said body also having spaced members formed with apertures generally in axial alignment, at least one of said members being resilient; detent means, interposed between said spaced members, and comprising a head, a shank, and an abutment formed intermediate said head and said shank, said head being slidably guided by the marginal surface of the aperture in one of said members for movement toward and away from the aperture in said portion, said abutment engaging said one member to limit movement of said head toward said conductor receiving aperture, and the extremity of said shank being slidably movable through the aperture in the other of said members; said detent means being of a greater overall length than the spacing between said members, so that said resilient member must be spread apart from the other member to provide for insertion of the head and shank of said detent means to position within the apertures of respective members; and spring means, disposed about said shank, and interposed between said abutment and said other member, said spring means urging said abutment to engagement with said one member.

7. Receptacle means, comprising: a body, having a portion provided with an aperture for receiving a conductor terminal, said body also hav-

ing spaced members formed with apertures generally in axial alignment; detent means, interposed between said spaced members, and comprising a head, a shank, and an abutment formed intermediate said head and said shank, said head being slidably guided by the marginal surface of the aperture in one of said members for movement toward and away from the aperture in said portion, said abutment engaging said one member to limit movement of said head toward said aperture, and the extremity of said shank stopping short of the other of said members; a washer, having an aperture aligned with the aperture in said other member, said washer aperture being adapted to slidably pass the extremity of said shank; and spring means, disposed about said shank, and interposed between said abutment and said washer, said spring means urging said abutment to engagement with said one member.

8. Receptacle means, comprising: a body, formed of a single strip of sheet-metal bent to generally S-shape, providing end walls and an intermediate wall arranged in generally parallel relation, and a pair of walls angularly disposed with respect to and connecting said end and intermediate walls; one of said connecting walls being apertured to receive a conductor terminal,

the adjacent end wall having a curved portion forming a continuation surface of said aperture; said intermediate wall being apertured, and the other of said end walls providing tab means adapted to secure said body to a support; a detent member, having one end working through the aperture in said intermediate wall; and resilient means, constructed and arranged to urge said one end of said detent member in a direction toward the aperture in said one connecting wall, to yieldably press a conductor terminal disposed in this aperture against said continuation surface.

9. Receptacle means, comprising: a body constructed of sheet material, having a vertical portion provided with an aperture for receiving a conductor terminal, said body having also spaced substantially horizontal planar walls formed with apertures disposed along an axis transverse to the conductor receiving aperture; detent means, slidably extending through and guided by said apertures, and having one end directed toward said receiving aperture; and exposed resilient means, constructed and arranged to yieldably urge said one end into engagement with a conductor disposed in said receiving aperture.

HARRY A. DOUGLAS.
